THERMOSTATIC VALVE MECHANISM

Thomas F. Van Denberg, Chagrin Falls, Ohio, assignor to The Titan Valve and Manufacturing Company, Cleveland, Ohio, a corporation of Ohio

Application January 6, 1947, Serial No. 720,349

5 Claims. (Cl. 158—127)

1

This invention relates to safe operating mechanism for a controlling device, by means of which the device may be reset or cocked to an active or operating position in which it is releasably held or maintained, subject to variation in a variable condition, such as temperature.

One object of the invention is to provide improved mechanism of the kind referred to, in which the controlling device is biased to move toward active position, but ordinarily, when all parts are cold, is held in inactive position, against its bias, by control means capable of actuation for control purposes and, more particularly, capable of actuation in such manner that it becomes ineffective upon the controlling device and permits its bias to become effective.

Another object is to improve the operating and control mechanism for such a controlling device, to simplify the same, reduce its cost and secure more certain and dependable operation.

Still another object is to provide improved control mechanism of the character described, in which the control means includes the members of a permanent magnet couple, together with means, sensitive to a variable condition, for controlling their approach into holding relation, or causing their separation for release or safety purposes.

Further objects of the invention in part are obvious and in part will appear more in detail hereinafter.

In the drawings, which represent one suitable embodiment of the invention, Fig. 1 is a longitudinal sectional elevation, showing the controlling device in inactive position;

Fig. 2 is a similar view, omitting certain parts, showing the operating parts in cocked position; and

Fig. 3 is a similar view, showing all parts in active or operating position.

The invention may be applied for use in the operation of any controlling device, such as an electric switch, a valve, a trigger or the like, employed in the control or operation of other devices. For convenience, and in no sense of limitation beyond the full scope of the claims appended hereto, it has been illustrated for use in the control of the flow of fluid, fuel, either gas or liquid, to a burner.

The drawings illustrate a main burner 10, to which fuel is supplied by a conduit 11, and a pilot burner 12 adjacent the main burner and supplied with fuel by way of conduit 13. The valve mechanism for controlling supply of fuel to the two conduits 11, 13 usually is organized

as a single unit, and is so shown, although this is not essential and separate control devices may be employed.

As illustrated, the controlling mechanism includes a hollow casing or body 14 provided with supply and discharge chambers 15, 16, either of which, such as chamber 15, communicates with a fuel supply pipe 17, and the other, 16, with conduit 11, flow from one chamber to the other being prevented or permitted by a main poppet valve 18, normally biased away from its seat 19 around the valve opening by compression spring 20, backed by a spring perch and valve guide 21 press fitted or otherwise secured in the tubular member 22 which lines the supply chamber. A union nut 23 compresses against a flange of tube 22 a fitting 24 to which supply pipe 17 is connected.

Valve 18 is attached to a tubular portion 25 of a valve support 26, the reduced end of which slides in guide 21 and is provided with a stop ring 27 limiting its motion. Within the hollow tubular portion 25 is mounted a suitable yielding thrust member, such as a light metal ball 28 backed by compression spring 29. Ordinarily, when all parts are cold, as shown in Fig. 1, ball 28 rests upon the large end portion 30 of a tube or rod 31, which thus yieldingly maintains the valve closed by compression spring 29, and also as by engagement of its flared flange 32, with the ball, limits motion of the tube to the left in Fig. 1. Tube 31 is biased outwardly by a compression spring 31a. Surrounding tube 31 is a cocking device, shown as a tube 33, provided with cap 34 and biased outwardly, or to the left in Fig. 1, by compression spring 35, an O-ring 36 sealing the joint between said tube 33 and the casing boss 37 in which it is slidable. The external diameter of tube 33 is the same as that of the enlarged end portion 30 of tube 31, while the inner end of tube 33 is internally beveled or thinned, as at 38, to correspond with the slope of the tapered portion 39 of tube 31.

The maintaining devices include the two cooperating members of a permanent magnet couple, either of which, such as permanent magnet 40, may be housed within and firmly secured to the enlarged end portion of tube 31, while the other in this case armature 41, is rigidly and immovably mounted in the body or casing 14. Magnet 40 also is mounted upon or attached to an axial valve rod or stem 42 which passes through an opening in the washer form armature 41, beyond which it is a close valve fit within, but is slidable in, a cylindrical valve seat or

opening in the body. Stem 42 is provided with an annular groove or channel 43 by means of which it functions as a pilot valve, preventing or permitting flow of fuel from supply pipe 44 through passage 45 to the conduit 13 leading to the pilot burner 12.

Outwardly beyond passage 45, the end of rod 42 lies opposite and in coaxial relation with, but is not attached to, the rod 46 of a thermostatic couple, the other tubular member 47 of which is threaded into the casing or body at 48. The members of this couple are of any conventional form, including two materials differing in their coefficients of expansion due to heat, arranged in such manner that upon rise in temperature, due, for example, to flame from pilot burner 12, the rod 46 retires, its inner or left hand end, Fig. 1, moving to the right, with opposite motion upon reduction in temperature.

The operation is as follows:

Fig. 1 shows the parts in their ordinary, inactive or normal positions, with all parts cold. A blank portion of rod 42 lies opposite passage 45 and prevents flow to the pilot burner. Main valve 18 is closed in safe position and is held closed by the yielding pressure applied to it through spring 29. Tubes 31 and 33 both lie in retracted position and the members of the permanent magnet couple are remotely apart or separated.

To cause operation of the burners, the cocking or resetting cap or button 34 is pushed in, either manually or by any suitable automatic operating device (not shown), thus advancing the parts to the positions shown in Fig. 2, motion being stopped or blocked by engagement of the end of valve rod 42 with the end of thermostatic rod 46. When this occurs at ordinary room temperature, the members of the permanent magnet couple are in blocking position. They have not yet reached holding relation or position, though they may be quite close together. In any event they are not within holding or maintaining range and will separate upon release of the cocking device.

During cocking or resetting, the first effect is to advance tube 33, while tube 31 is held stationary by spring 31a until the beveled inner end of tube 33 abuts tube 31 and carries it along, the two moving together. Now they act as one, traveling along beneath ball 28, which rides onto tube 31 and is thus maintained in valve closing position to the full end of the advance cocking motion, before described.

With the parts cocked, as in Fig. 2, the pilot valve has been opened by advance of valve channel 43, and fuel flows to the pilot valve. While continuing to maintain finger pressure upon the cocking button, the pilot valve is ignited and promptly heats the thermostatic couple. As the temperature rises, tube 47 elongates and permits rod 46 to retire, thus permitting further slight advance motion of all parts affected by the applied finger pressure, including magnet 40, which reaches holding relation or position with respect to its mate. In this position magnet 40 either contacts armature 41 or, if separated therefrom by dirt particles or other non-magnetic material, is so close to it that it is held or maintained thereby until later release, as will appear.

Now, upon release of the resetting button, the tube 33 retires but leaves the tube 31 with attached parts behind. Thus the ball 28 drops off from the end of tube 33, all parts finally

reaching the active position shown in Fig. 3. Here, the ball rests upon the small diameter portion of tube 31 and valve 18 has been advanced to open or active position by spring 20. Fuel flows to the main burner and is there ignited by the pilot burner.

Burner operation continues, possibly with some regulating action of the main burner by conventional graduating or snap acting valve mechanism (not shown) until, for any reason both the pilot and main burner flames go out, permitting the parts to cool. This permits the thermostatic tube 47 to contract and causes rod 46 to advance to the left in Fig. 3, communicating its motion to rod 42 and the magnet attached thereto and thus physically and bodily separating the two members of the magnet couple. As soon as they lose contact with each other, the retracting spring 31a becomes effective and retracts tube 31, its tapered wall 39 serving as a cam and restoring ball 28 to its original position and thus yieldingly closing main valve 18.

All parts are now in their original positions ready for another cycle of operations.

The arrangement described is simple, is satisfactory and reliable in service, may be made and sold at low cost, and requires practically no service or repair.

Other advantages of the invention will be apparent to those skilled in the art.

What I claim is:

1. Thermostatic valve mechanism, comprising a magnet couple including cooperating mated magnet and armature members, one fixed and the second movable toward and from its mate, a reciprocable valve biased to advance from closed to open position, the movable couple member being biased toward a retracted position remote from its mate where it obstructs valve advance and thus maintains the valve closed, manually operated reset means biased to a retracted position and effective when advanced to both engage the valve and maintain it closed and at the same time advance the movable couple member to an intermediate position out of obstructing relation to the valve and close to but out of contact with its mate and thus short of holding relation therewith, a main burner, a pilot burner adjacent said main burner, and thermostatic means sensitive to heat produced by said pilot burner and which when cooled prevents and when heated permits further advance of the movable couple member by the reset means beyond said intermediate position into contacting relation with its mate, the magnetic flux between the couple members being insufficient to overcome the bias upon the movable couple member when they are closely spaced but being sufficient to do so when they reach contacting relation, whereby release of the advanced reset means when the thermostatic means is heated permits the valve to advance to open position.

2. Thermostatic valve mechanism, comprising a magnet couple including cooperating mated magnet and armature members, one fixed and the second movable toward and from its mate, a reciprocable main valve biased to advance from closed to open position, the movable couple member being biased toward a retracted position remote from its mate where it obstructs main valve advance and thus maintains the main valve closed, manually operated reset means biased to a retracted position and effective when advanced

to both engage the main valve and maintain it closed and at the same time advance the movable couple member to an intermediate position out of obstructing relation to the main valve and close to but out of contact with its mate and thus short of holding relation therewith, a main burner, a pilot burner adjacent said main burner, a pilot valve movable back and forth with the movable couple member from closed position when said member is retracted to open position when said member is in said intermediate position, and thermostatic means sensitive to heat produced by said pilot burner and which when cooled prevents and when heated permits further advance of the movable couple member by the reset means beyond said intermediate position into contacting relation with its mate, the magnetic flux between the couple members being insufficient to overcome the bias upon the movable couple member when they are closely spaced but being sufficient to do so when they reach contacting relation, whereby release of the advanced reset means when the thermostatic means is heated permits the main valve to advance to its open position.

3. Control mechanism of the character described, comprising a reciprocable valve biased to advance in one direction along a line from closed to open position, means for normally maintaining said valve closed, comprising a magnet couple including cooperating mated permanent magnet and armature members relatively movable along a second line intersecting said first line, one thereof being movable, spring means for biasing said movable member to retract to a position spaced from its mate by a force strong enough to retract the valve to closed position against its bias, the other member being stationary, the magnetic flux between the couple members being strong enough to overcome the bias upon the movable member when the couple members are in contacting relation but insufficient to that end when they are spaced apart, said movable member being provided with holding means constructed and arranged to normally maintain said valve closed when said movable member is in retracted position, a resetting member reciprocable along said second line and biased toward retracted position and arranged when advanced toward one position to obstruct advance motion of said valve, and when advanced to a second position to advance said one couple member into contacting relation with its mate, and when retracted to release said valve for advance to open position, means sensitive to temperature variable around a pre-established critical value, and having a part movable to hold the movable couple member short of contacting relation with its mate when the temperature is below the critical value, but withdrawable to permit the movable couple member to be advanced to contacting relation with its mate when the temperature is above the critical value, and cam means on said holding means and effective, when said couple

member is retracted, to contact and return said valve to its closed position.

4. Control mechanism of the character described in claim 3, including a pilot valve operatively connected to and movable with said movable member and arranged to open during the first advance motion thereof.

5. Apparatus of the character described, comprising a magnet couple including mated magnet and armature members, one fixed and the other movable towards and from its mate, a control device movably carried adjacent the magnet couple and reciprocable between a first safe and a second operating position responsive to manipulation of said magnet couple, spring means for biasing said movable couple member towards a retracted position remote from its mate, and, while in such retracted position, having a part disposed to contact and obstruct advance of the control device toward operating position and thus normally to maintain said device in its safe position, manually operated reset means, other spring means for biasing said reset means to a retracted position, and effective when advanced to both 10 engage the control device and maintain the same in its first safe position and at the same time to advance the movable couple member to an intermediate position out of contacting and obstructing relationship to the control device and close to 15 but out of contact with its mate, and thus short of holding relation therewith, and means sensitive to a condition variable around a predetermined critical value including a movable part which under a first condition on one side of the 20 critical value obstructs further advance of the movable couple member by the reset means into contact with its mate and under a second condition on the other side of the critical value is withdrawn to permit further advance of the movable couple member by the reset means into contact with its mate, said condition responsive means being operative, upon return of said first condition to contact and return said movable couple member to retracted position, the magnetic 25 flux between the couple members being insufficient to overcome the bias upon the movable couple member when they are closely spaced but out of contact but being sufficient to do so when they are in contact, whereby release of the advanced reset means, while the second condition exists, permits the biased control device to advance to its second operating position.
